K. SCHMIDT

FIRE EXTINGUISHER

Filed Feb. 1, 1924

FIG. 1.

FIG. 2.

Inventor:
Karl Schmidt,
By *Knight Bros*
Attn:

UNITED STATES PATENT OFFICE.

KARL SCHMIDT, OF NEURUPPIN, GERMANY.

FIRE EXTINGUISHER.

Application filed February 1, 1924, Serial No. 690,023, and in Germany February 1, 1923.

My invention relates to fire extinguishers with siphon arrangement and a stop valve at the discharge pipe. In the ordinary extinguishers with a discharge pipe which do not possess a siphon arrangement, the discharge pipe acts during the charging, provided they are turned upside down, as an overflow, so that the prescribed air space is produced automatically. This effect can, however, not take place in fire extinguishers of the type under consideration, as in the inverted charging position the discharge pipe is closed by the stop valve. The siphon pipe or pipes, of which two are generally employed, can, however, not be utilized for producing the air space, either because when the liquid rises in the apparatus during the charging up to the bend or knee of the siphon pipes, these pipes commence to act as siphons, so that through them and the spraying nozzle not only the surplus of liquid charged into the apparatus flows off but sometimes the entire contents of the extinguisher. Attempts have been made to eliminate this drawback by carrying the knee of the siphon pipes up as high as possible, that means close up to the bottom of the extinguisher shell, so that it was no longer reached by the liquid rising in the extinguisher during the charging, and by simultaneously housing the valve, which is destined to close the discharge pipe during the operation of the siphon pipes when the extinguisher is in use, during the duration of the charging process in a pocket-like extension of the valve casing. The manipulation of the extinguisher in order to convey the ball valve into this pocket-like extension or trap offers, however, some difficulties to the unexperienced operator, or at least demands his special attention in the absence of which the extinguisher may be overcharged or partly or entirely discharged by the action of the siphon pipe started by the overcharge. In order to attain that also in fire extinguishers of the present kind the necessary air space is automatically generated, according to this invention the siphon pipes are employed as overflow pipes. To avoid that the siphon tubes act as siphon during the charging process, an arrangement has been made that from the highest point of the siphon pipes a thin tube branches off, which allows air to enter into the siphon tube or tubes, so that the

pipes can not act as siphons. As long as the air inlet tube is open, the siphon pipes operate simply as overflow for the liquid charged into the apparatus. The apices of the siphon pipes are arranged at that level up to which the extinguisher should be charged. In order that during the operation of the extinguisher the siphon pipes may again act as siphon the before mentioned air inlet tube joined at the apex of the siphon must be closed again after the charging of the extinguisher. This may be effected by carrying the small tube up to the edge of the charging opening of the extinguisher, so that during the closing of this opening by means of the closing piece it will simultaneously be sealed by its packing disc.

In adopting this arrangement the stop valve of the discharge pipe may be constructed considerably simpler and more suitable, inasmuch as a pipe is inserted into the valve chest, which terminates at some distance from the valve seat, guides the ball valve and withdraws it from the action of the liquid flowing into the valve chamber during the ejection of the extinguishing liquid from the extinguisher through the discharge pipe. A valve of this construction demands only about two thirds of the height of the valves hitherto employed in apparatus of this kind, as the valve casing may be perforated up to its cover and need not have an unperforated portion of considerable height, as heretofore.

The accompanying drawing illustrates an embodiment of my invention.

Fig. 1 is a vertical longitudinal section through the improved extinguisher and Fig. 2 is a section through the casing of the valve which seals the discharge pipe during the operation of the siphon pipe.

The same letters of reference indicate similar parts in both figures of the drawing.

Referring to the drawing *a* is a fire extinguisher of any suitable shape fitted with a discharge pipe *b* and one or a plurality of siphon pipes *c*. On the drawing only one pipe *c* is shown. In known manner pipes *b* and *c* end in a chamber *u* which in turn communicates with nozzle *t*. The casing *d* contains the valve sealing the discharge pipe *b*. The knee or bend of the siphon pipe *c* is situated at that level up

to which the level of the extinguishing liquid should rise during the charging of the apparatus. From the knee of the siphon pipe branches off a thin tube *g*, which extends up to the outer sealing face of the charging branch *h*, so that the packing plate *i* of the sealing piece *m* which is screwed on the threads of the filling opening *h* and closes the charging opening *h* simultaneously closes the mouth of the small tube *g*. If a plurality of siphon pipes are employed the small tubes *g* may be united to form a single tube, which is then closed by the packing plate *i*.

At the bottom *n* of the valve casing *d*, see Fig. 2, a pipe *o* is arranged, the diameter of which is less than that of the casing. This pipe terminates in front of the seat surface *p* for the ball valve *e* at a distance, which corresponds approximately with the width of the annular space *q* between the casing *d* and the pipe *o*. As shown in the drawing the ball *e* is entirely withdrawn from the influences of the liquid flowing in through the openings *r* when squirting upwards with the extinguisher. In contradistinction to the hitherto known valves for fire extinguishers of the described type, the bottom *n* of the valve chamber may also possess inlet openings for the extinguishing liquid opposite the annular space *q*.

It will be understood that I do not limit myself to the exact construction shown and described, but the modifications within the ambit of the claims will easily suggest themselves to those skilled in the art.

What I claim as my invention and desire to secure by Letters Patent is:—

1. In a fire extinguisher, a siphon outlet pipe having its bend at the charge level, and an air inlet tube connected to said pipe at its bend. 40

2. In a fire extinguisher, a siphon outlet pipe having its bend at the charge level, an air inlet connected to said pipe at its bend, and means for closing said tube. 45

3. In a fire extinguisher, a siphon outlet pipe having its bend at the charge level, an air inlet tube connected to said pipe at its bend, said tube debouching at the filling 50 opening of the extinguisher, and common closure means for said tube and the filling opening.

4. In a fire extinguisher, a discharge pipe, a ball valve at the influent end of said pipe, 55 and a sleeve within said pipe into which said ball moves when the extinguisher is in operative position, said sleeve acting to prevent the inflowing fluid from moving the ball against its seat. 60

5. A valve comprising a cup having a constricted outlet, a ball adapted to seat against said constricted outlet by gravity upon tilting of the valve, and a sleeve within said cup into which said ball is adapted to roll 65 on tilting of the valve in the opposite direction, said sleeve acting to prevent the fluid flowing through said cup from moving the ball against its seat.

In testimony whereof I affix my signature.

KARL SCHMIDT.
